COMBINED MONEY CLIP AND WATCH

Alex Fenster, Forest Hills, N.Y., assignor to Fit-Rite
Watch Case Corporation, a corporation of New York

Filed Sept. 25, 1961, Ser. No. 66,832

Term of patent 14 years

(Cl. D17—3)

Fig. 1

I claim:

The ornamental design for a combined money clip and watch, as shown.
